UNITED STATES PATENT OFFICE.

RICHARD LUDWIG, OF BOUS-ON-THE-SAAR, GERMANY.

ROLLING-MILL.

1,122,013.

Specification of Letters Patent. Patented Dec. 22, 1914.

Application filed April 24, 1914. Serial No. 834,244.

To all whom it may concern:

Be it known that I, RICHARD LUDWIG, a subject of the Emperor of Austria-Hungary, residing at 441 Mannesmannstrasse, Bous-on-the-Saar, Germany, have invented certain new and useful Improvements in Rolling Mills; and I do hereby declare the following to be a full, clear, and exact description of the invention.

10 My invention relates to rolling mills and particularly to rolling mills of the step by step advance type in which a spring-pressed mandrel mounted on the feed slide carries the blank and advances it to the roll while 15 a fluid brake limits the forward travel of the mandrel and blank.

The devices commonly used for rotating the mandrel and blank in mills of this type are objectionable for the reason that they 20 comprise heavy masses such as shafts, and the like, the operation of which makes heavy demands upon the apparatus. Furthermore, these devices are commonly arranged in extension of the mill proper and consequently 25 occupy a great deal of mill room. The present mandrel and blank rotating devices lessens these disadvantages by the use of a high pitch feed screw carried by the mandrel slide and working in a threaded portion or sleeve 30 of a hollow brake piston which moves with the mandrel. The feed screw, by which the mandrel is rotated during its advance, is arranged in the interior of the brake piston or its rod. Consequently the length and the 35 weight of the reciprocating parts is minimized and the necessary operating power lessened, or for a given operating power a speedier action is attained.

In the accompanying drawings Figures 1 40 to 5 are longitudinal sections through five different embodiments of my invention. Fig. 1¹ and 1² are cross-sections on the line A—B and C—D in Fig. 1.

In the arrangement shown in Fig. 1 a a 45 fluid container *g* is fast with the usual slide *s*, which is advanced by means of the screw spindle *s'* or a hydraulic piston toward the rolls *r* during the intervals between the attacks of the latter upon the blank *w*. The 50 latter is mounted on a mandrel *m* and is driven back by the attack of the rolls in the direction of the arrow 1 to the right together with the mandrel *m* and a brake piston *a* fast with the mandrel. The brake piston 55 has the form of a hollow plunger and carries within it a piston *b* with which the feed

screw *h* is fast. The hollow rod *b'* of piston *b* carries a ratchet gear *i* by means of which and a pawl *i'* the piston *b* is held in position in the forward movement of the plunger *a* and mandrel *m*. In the chamber *c* means are provided for driving forward the blank to the roll attack. Any suitable pressure means may be employed for this purpose, for example air or gas which has been compressed by the backward thrust of the blank and mandrel by the rolls. When compressed air or gas is thus employed it is admitted to the chamber *c* through the hollow rod *b'* of the piston *b* connected by tubing *f* with a pressure reservoir *p*. The container *g* on the mandrel slide is filled with the braking fluid. On the feed, the piston *a* (and with it the mandrel and blank) is driven forward in the direction of the arrow 2 by the pressure in chamber *c* and is halted at the proper moment through the braking action of the fluid in *g* as explained in the patent to Nowak 1,041,661. On the backward movement of the blank and mandrel under the impact of the rolls, the pressure means in chamber *c* is again put under tension.

The rotation of the blank and mandrel is accomplished on the advance of the latter to the rolls through the high pitch screw *h* which is threaded into the interior of the piston *a* and is held in position by the ratchet gear *i* and pawl *i'*. On the backward thrust of the mandrel and blank by the rolls a rotation of the ratchet gear *i* with piston *b* and screw *h* takes place. The co-operating threads *a'* on the piston *a* are arranged in this case on a forward extension of the piston through which the screw *h* passes.

In the arrangement shown in Fig. 2 the threads *a'* are arranged at the other end of the piston *a* which is now in the form of a hollow box. The ratchet gear *i* is fast with the screw rod *h* and the latter has now a bore *h'* which communicates through an opening *h*² with the chamber *d*, so that the air or gas is admitted by means of the hollowed screw rod *h* to the chamber *c* from the chamber *d* with which the pressure reservoir communicates through pipe *f*.

In the arrangement shown in Fig. 3 the rear of the brake plunger *a* is enlarged to form a piston *n* working in the chamber *d* and thus more efficiently compressing the air on the backward thrust of the blank by the rolls.

In Fig. 4 the piston *a* is constantly confined in a cylinder *c* formed in the mandrel slide *s*, the forward end of which communicates through openings *c'* with the fluid pressure chamber *g*.

In Fig. 5 the brake piston or plunger *a* engages a stem *h*³ which has a series of straight splines *h*⁴. The latter are slideable in a correspondingly formed nut *a*² of the plunger *a*. The rearward end of the stem *h*³ is connected with a spindle *l* freely rotatable in the end of the slide *s*. The spindle *l* with stem, plunger, mandrel rod and blank is rotated between attacks of the rolls upon the blank in an ordinary manner by means of a toothed wheel gearing *t* and interposed spring *v*.

I claim as my invention:

1. In a rolling mill of the type described, a feed slide, a mandrel rod supported thereby, a brake piston on said mandrel rod, a member carried by said feed slide and held against longitudinal displacement thereon but in sliding engagement with said brake piston and means operative through said piston and engagement for intermittently rotating the mandrel rod, substantially as described.

2. In a rolling mill of the type described, a feed slide, a mandrel rod supported thereby, a brake piston on said mandrel rod, a member carried by said feed slide and held against longitudinal displacement thereon, but having a threaded engagement with said brake piston for rotating the latter on the longitudinal displacement thereof, substantially as described.

3. In a rolling mill of the type described, a feed slide, a mandrel rod supported thereby, a brake piston on said mandrel rod, a member carried by said feed slide and held against longitudinal displacement thereon, but having a threaded engagement with said brake piston for rotating the latter on the longitudinal displacement thereof, together with a ratchet mechanism for holding said threaded member against rotation in one direction.

In testimony whereof I have signed my name to this specification, in the presence of two subscribing witnesses.

RICHARD LUDWIG.
